UNITED STATES PATENT OFFICE.

JOHN WALLACE LAURENT, OF SPOKANE, WASHINGTON.

CURRENT-MOTOR.

No. 841,547.

Specification of Letters Patent.

Patented Jan. 15, 1907.

Application filed August 24, 1905. Serial No. 275,554.

To all whom it may concern:

Be it known that I, JOHN WALLACE LAURENT, a citizen of the United States, and a resident of Spokane, in the county of Spokane and State of Washington, have invented a new and Improved Current-Motor, of which the following is a full, clear, and exact description.

This invention relates to improvements in motors operated by the water of flowing streams, the motor being especially adapted for elevating water for irrigating purposes, the object being to provide a current-motor of simple and novel construction that will be self-regulated to the rise and fall of the water and that may be operated by a comparatively light current.

Other objects of the invention will appear in the general description.

I will describe a current-motor embodying my invention and then point out the novel features in the appended claims.

Reference is to be had to the accompanying drawings, forming a part of this specification, in which similar characters of reference indicate corresponding parts in all the figures.

Figure 1 is a plan of a current-motor embodying my invention. Fig. 2 is an elevation thereof. Fig. 3 is an elevation at right angles to Fig. 2. Fig. 4 is a broken sectional detail showing the float, the driving-shaft, and parts carried thereby. Fig. 5 is a face view of one of the blades. Fig. 6 is an end view thereof. Fig. 7 is a section on the line $\times \times$ of Fig. 5. Fig. 8 shows a blade in lowered position. Fig. 9 shows the same raised. Fig. 10 indicates a releasing-trip employed. Fig. 11 shows a means for taking up the slack of the transmission-cable, and Fig. 12 indicates one of the water-elevating buckets.

The frame of the motor comprises a base 1, having uprights or posts 2, connected at the top by a beam 3. The uprights 2 are braced from lateral movement by bars 4, extending upward from the base 1 to connection with the upper ends of said uprights, and the frame may be further braced by bars 5, extending at an angle from the ends of the beam 3 to the upper ends of standards 6, which are connected by a cross-bar 7. Arranged to move vertically in the frame is a float 8, which, as clearly indicated in the

drawings, is of box-like form, closed at the ends, sides, top, and bottom. The float has projections at its ends engaging in channels formed in the uprights 2, and secured to the upper side of the float at its center is a metal plate 9, having a raceway 10 for bearing-balls 11, the said balls also engaging in a raceway formed in a bearing-plate 13, from which a series of arms 14 radiates, the several arms being braced at their outer ends by rods 15. While I have shown eight of these arms 14, it is obvious that a greater or less number may be employed without departing from the spirit of my invention. The bearing-plate 13 has a tubular or socket member 16, which passes through the hub of the several arms 14, and keyed in said socket member is the operating-shaft 17, rigidly connected to which is a casting 18, and from this casting truss-rods 19 are extended to connection with the arms 14 near the outer ends. The shaft 17 passes loosely through an opening in the beam 3 and also loosely through a bearing-plate 20 on said beam, the said bearing-plate being provided with a raceway for bearing-balls 21, which engage also in a raceway in a plate 22, having splined connection with the shaft, so that the said shaft may slide vertically, but also cause movement of the said plate 22, and also connected to the shaft and bearing upon the plate 22 is the driving-sheave 23. The sheave has a spline connection with the shaft, so that the shaft may slide vertically therethrough, and the arrangement of the plates 20 and 22 relieves the float from the weight of the driving-sheave. Having hinged connection with each arm 14 is a blade or paddle 24, the hinged connection being such as to permit the blade or paddle to swing from a vertical to a horizontal plane, as will be hereinafter described. Each blade at its outer end is curved or inclined, as at 24^a in Figs. 1 and 7, in the direction in which the blade moves. By this construction when the blade falls toward its operative position the incline will receive the current-pressure immediately, causing the blade to assume its vertical position, and this is not found to be the case with a blade straight throughout its length. Each blade is provided at its outer end near the bottom with a roller 25, designed to engage on the upper side of an inclined plate 26, attached to one end of the float 8, so as to move

the blade upward to its horizontal position and into engagement with a spring-hook 27, attached to the bar 15. The blades are held while in the water in vertical position by means of chains 28, connected at one end to the bars 15 and at the other end to the blades near the lower edge, and as a means for drawing the chains upward when the blades are moved to horizontal position I employ spring-
10 rods 29, which have coiled portions 30 connected to the arms and link connections 31 with the chains.

At the end of the float opposite the incline 26 is a tripping device for releasing the hooks 27 from the blades, permitting said blades to fall by gravity into the water to be operated upon by the current. As here shown, this tripping device consists of a plate 32, extended upward from a base-plate 33, which is provided with slots through which bolts 34 pass into the float. A spring 35 on the float has its free end engaged in an opening in the trip-plate 32, and from the outer end of this trip-plate a draw-line 36 extends to the shore, the object of which will be hereinafter described. From the operating-sheave 23 a transmission-cable 37 passes over idlers 38, thence around tension-pulleys 39, mounted on a shaft 40, which has its bearings in a frame 41, mounted to slide vertically in guide-channels formed in uprights 42, as clearly indicated in Fig. 11. The weight of the frame and pulleys 39 will take up the slack of the transmission-cable. If greater weight is required, however, the same may be attached to an eyebolt 43 on the lower cross-bar of the frame 41. From the pulleys 39 the transmission-cable passes over a sheave 44 on a shaft 45, arranged at the upper end of an elevator tower or frame 46. On the shaft 45 are sprocket-wheels 47 engaged by endless chains 48, the said chains also passing around sprocket-wheels 49 at the lower portion of the tower. Connected to these endless chains 48 are water carrying 40 or elevating buckets 50, these buckets being of box-like form and open at the top.

In the operation certain of the blades will extend into the water to be operated upon by the current-pressure at one side of the shaft 50 17. Upon approaching the opposite side of the shaft the blades will be raised to horizontal position by means of the incline 26, as before mentioned, and will be held in such position by the hooks 27 until they again reach 55 the opposite end of the float, when the hooks will come in contact with the trip-plate 32 and be sprung out of engagement with the blades, permitting them to fall by gravity. Of course as the blades rotate motion will be 60 imparted to the shaft 17, causing the operation of the elevating-buckets, which will discharge water into a trough or sluice 51. When it is desired to stop the motor, the

trip-plate 32 is to be drawn outward by means of the draw-line 36, so as to permit 65 the hooks 27 to pass and hold the several blades in horizontal position above the water-level.

Having thus described my invention, I claim as new and desire to secure by Letters 70 Patent—

1. A current-motor comprising a float, arms mounted to rotate on said float, transmission mechanism operated from said arms, blades having hinged connection with the 75 arms, bars connecting the outer ends of the arms, flexible connections between the lower edges of said blades and the bars, springs having connection with the bars and with said flexible connections for drawing said 80 flexible connections upward as the blades are moved to horizontal position, means for causing the blades to move to horizontal position, means for locking the blades in horizontal position at each revolution of the 85 wheel, and means for automatically releasing the locking devices.

2. A current-motor, comprising a float, radial arms mounted to rotate on the float, transmission mechanism operated from said 90 arms, and blades having swinging connection with the arms, the outer portions of said blades being inclined in a direction in which the blade is moving.

3. A current-motor, comprising a float, a 95 frame in which the float is guided, radial arms mounted to rotate on the float, blades having swinging connection with the arms, rollers on the outer ends of said blades, an incline at one end of the float, with which 100 said rollers are designed to engage to move the blades to horizontal position, means for locking the blades in said horizontal position, means at the opposite end of the float for releasing the locking devices and means for 105 shifting said releasing means out of releasing position.

4. A current-motor comprising a float, arms mounted to rotate on the float, a shaft 110 extended upward from the arms, rod connections between said shaft and the arms, a sheave arranged to rotate with the shaft, but through which the shaft is vertically movable by the rise and fall of water, swinging blades carried by the arms, means for locking the 115 blades in inoperative position at each rotation of the wheel, and means for releasing the blades to move to operative position.

5. In a current-motor, a plurality of radial arms mounted to rotate in a horizontal 120 plane, blades carried by the arms, a shaft extended upward from the arms, a sheave on said shaft, a tower, sprocket-wheels at the upper portion of said tower, sprocket-wheels at the lower portion of said tower, a sheave 125 on the shaft of the upper sprocket-wheels,

chains engaging with the sprocket-wheels, buckets carried by said chains, a transmission-cable extending from the first-named sheave to the second-named sheave, idlers 5 over which said transmission-cable passes, and tension-rollers with which the cable engages.

In testimony whereof I have signed my name to this specification in the presence of two subscribing witnesses.

JOHN WALLACE LAURENT.
